UNITED STATES PATENT OFFICE.

JOHN F. McNAMARA, OF DANBURY, CONNECTICUT.

TOY BOWLING GAME.

1,133,810.

Specification of Letters Patent.

Patented Mar. 30, 1915.

Application filed December 12, 1914. Serial No. 876,898.

To all whom it may concern:

Be it known that I, JOHN F. McNAMARA, a citizen of the United States, residing at the city of Danbury, county of Fairfield, 5 and State of Connecticut, have invented certain new and useful Improvements in Toy Bowling Games; and I do declare the following to be a full, clear, and exact description of the invention, such as will enable others skilled in the art to which it appertains to make and use the same.

This invention relates to certain new and useful improvements in toy bowling apparatus, and pertains more particularly to 15 that type of bowling apparatus in which the pins are movably supported so as to swing out of the path of the balls when they are hit by the latter and in which the balls are projected by means of mechanical projecting 20 apparatus.

The invention has for one of its objects to provide a bowling apparatus in which the pins are pivoted to swing in a vertical plane, and are held raised up from the alley and 25 out of the path of the ball after they have once been struck.

A further object of the invention is to provide novel and improved means for resetting the pins for the next frame after the preceding frame has been rolled.

A still further object of the invention is to provide means for returning the balls after each frame has been rolled to a position adjacent and readily accessible to the player.

35 A further object of the device is to provide coin controlled mechanism for releasing the balls and depositing them in suitable receptacles for the players.

With the above and other objects in view, 40 reference will be now had to the accompanying drawings, in which:

Figure 1 is a top plan view of the invention; Fig. 2 is a sectional view on the line 2—2 of Fig. 1; Fig. 3 is a cross sectional view on the line 3—3 of Fig. 2, showing the pin setting mechanism, in section, and in fragment; Fig. 4 is a perspective view of one of the pins; Fig. 5 is a front elevation of the invention; Fig. 6 is a vertical sectional view 45 taken on the line 6—6 of Fig. 1; Fig. 7 is a sectional view on the line 7—7 of Fig. 6, showing one of the ball returns broken away, and the other ball return removed; Fig. 8 is a sectional view of the coin controlled 50 mechanism, taken on the line 8—8 of Fig. 6; Fig. 9 is a vertical sectional view partly in

elevation, of the coin controlled mechanism operating means; and Fig. 10 is a perspective view of the pin retaining and resetting mechanism.

Referring more particularly to the drawings, the numeral 1 designates a base which is suitably supported by legs 2 at one end and a box like portion 3 at its opposite end. The base 1 is made sufficiently wide to accommodate two spaced bowling alleys 4 and 5, the latter being arranged side by side, as shown in Fig. 1. The base 1 is provided with side boards 6, spaced from the outer side edges of the bowling alleys 4 and 5, to provide outer gutters 7, while in the space separating the bowling alleys 4 and 5, and spaced therefrom is a partition 10 which also provides gutters 8 on opposite sides thereof. At the rear ends of the alleys, the side boards 6, and the central partition 10 are curved 75 upwardly to provide aprons or the like 12 to prevent the balls from flying from one alley to the other, or out of the alleys. The rear ends of the alleys 4 and 5, and the base 80 1, terminate short of the legs 2 to provide a pit 13 which is hopper-like in structure, and is adapted to receive the balls after they have hit the pins.

Supported by the base 1, are two inverted 85 U-shaped members 15 arranged one over each alley, and pivoted to the tops of the U-shaped members by means of eyes 16 are the pins 17, there being five pins for each alley.

Between the rear ends of the alley and the U-shaped members 15 is a U-shaped member 20 having vertically extending legs 21, and a base member 22 which connects the legs 21, the member 22 being mounted for sliding 95 engagement under the alley. One of these members 20 is provided for each alley.

Mounted in the legs 21 of the U-shaped members 20 near the upper end thereof are two parallel rods 25 and 26 and above these 100 rods 25 and 26 and arranged centrally thereof is a third rod 27, the purpose of which will appear hereinafter.

Pivoted to the rearmost rod 26 of the two rods 25 and 26 are sheet metal latching 105 members 28, the forward ends of which rest on the foremost rod 25, and are supported by the latter against downward movement.

The opposite sides of the U-shaped members are provided with integral lugs or projections 30 which slide in slots 31 in the side boards 6 and partition 10, to guide the U-

shaped members in their reciprocal movement longitudinally of the alley.

Connected centrally to the base portion 22 of the U-shaped members 20 at 32 is a rod 33, which rod extends to the forward end of the alleys and has secured to the end thereof a knob 34 for manual manipulation.

Fastened at one end to lugs 35 integral 10 with the base portion 22 of the U-shaped members 20, are springs 36, the other ends of which are connected as at 37 to the base 1.

Secured on the inner face of the front wall 40 of the box-like support 3 is a coin 15 chute 41, and pivoted at 42 in the side walls of the box-like support is a rod 43. Rod 43 has integral therewith a platform 44, the free end 45 of which projects into the coin slot 41 as shown in Fig. 7.

20 Integral with the pivoted rod 43 are two platforms 46 and 47, and extending rearwardly from each of the platforms 46 and 47 is an arm 49, which is provided with an adjustable weight 50.

25 Extending forwardly from each of the hopper-like pits 13 is an inclined trough-like ball return 51, the bottom of which is cut away at 52 to deliver the balls upon the platforms 46 and 47, the platforms being 30 held upwardly against the cut-out portions of the ball returns by means of the weights 50.

35 Directly opposite the platforms 46 and 47, the front wall 40 of the box-like support 3 is provided with openings 53 and 54, the purpose of which is to permit of the passage of the balls from said platform to the pockets 55 and 56.

40 Supported by the front wall 40 of the forward support 3 on the interior thereof is a box 57 which is mounted adjacent to, and lies parallel with the coin chute 41.

45 The side of the box 57 adjacent the coin chute 41 is provided with a slot 58, the upper portion of which is out of vertical alinement with the remainder of the slot as at 59 (see Fig. 9) for a purpose to be hereinafter set forth.

50 Above the box 57 and supported by the wall 40 is an eye 60, and projecting through a slot 61 in the front wall 40 is a lever 62 having a handle 63 on one end, and having its other end bent downwardly and extending through the eye 60 and into the box 57.

55 Surrounding the downwardly extending portion of the lever 62 and having one end engaging the eye 60, and the other end engaging a collar 65 on the lever is a spring 66, the purpose of which is to return the 60 lever to normal up position after it has been depressed.

65 The lever has secured to its lower end, a right angular extension 70 which is received and guided in its vertical movement by the angular slot 59 to carry the extension 70 out

of the path of the coin when the parts are in their normal position.

As shown in Fig. 1 of the drawings, pistols 75 may be used to shoot the balls 76 at the pins, but it will of course be understood 70 that the balls may be moved down the alleys by an ordinary billiard cue or they may be shot by the hand as in playing the game of marbles.

The operation is as follows: A coin upon 75 insertion in the coin slot 41, gravitates until it rests upon the platform 44. The handle 63 is now depressed to thus force the right angular extension 70 down through the coin slot until it engages the coin. Engagement 80 of the right angular extension with the coin rocks the shaft 43, and throws the platforms 46 and 47 downwardly and permits of the balls 76 rolling through the opening 53 into the pockets 55. The balls are then 85 taken by the player and shot along the alley at the pins by means of the pistols or any suitable device. The balls upon hitting the pins rock the latter about their pivotal support to the position shown in dotted lines in 90 Fig. 2, and in their upward movement the pins engage and move the pivoted latching members 28 upwardly. The pivoted latching means will fly upward until they engage the transverse bar 27 when they are arrested 95 and immediately fall down to normal position. The pins in their movement to down position engage the latching members as in Fig. 2 and are thus retained out of the path of the balls until the pins are reset. To reset 100 the pins the rods 33 are pushed against the action of the springs 36 which moves the U-shaped members in the guides 31 thus moving the latching means out from under the pivoted pins and allowing the pins to 105 swing downwardly to normal position. Under the influence of the springs 36 the U-shaped member 20 is returned to its normal position where the pins will be engaged by the latching means upon the next operation. 110 The balls after hitting the pins pass into the hopper shaped pit 13 and are returned by the inclined ball returns 51 to the platforms 46 and 47, where they are retained until the insertion of another coin and operation of the coin controlled mechanism.

What is claimed is:

1. In a toy bowling apparatus, a pin support, a plurality of pins pivotally secured thereto, pivoted latching means for the pins, 120 said latching means being slidable to release the pins, and means for sliding the latching means.

2. In a bowling apparatus, a bowling alley, a plurality of pins pivoted above the 125 alley, a spring pressed frame movable relative to the pins, means to operate the frame against the action of the spring to move the frame away from the pins, and individual latches, borne by the frame and movable 130

independently thereof by the pins striking same and movable bodily with the frame.

3. A toy bowling apparatus, comprising, a stationary pin support, a plurality of pins pivoted to said support above the alleys, a spring retracted frame, a plurality of pin latching means carried by said frame, and means for moving the frame carrying the pin latching means to release the pins.

10 4. A toy bowling apparatus comprising a stationary pin support, a plurality of pins pivoted to said pin support, a frame behind the pin support, a plurality of pivoted latches on the frame adapted to support the pins, and means for moving the latches longitudinally of the alleys to release the pins.

15 5. A toy bowling apparatus comprising a plurality of bowling alleys, a pin support rigidly supported above each alley, a plurality of pins suspended from said pin support, a frame behind the pin support, a plurality of latches pivoted in said frame, a stop for the latches, a ball chute for returning the balls to the front of the alleys, and 25 coin controlled means for releasing the balls.

6. A toy bowling apparatus, comprising in combination with a bowling alley, a pin support, a plurality of pins pivoted to said pin support, a frame slidable with respect 30 to the alleys, a plurality of pin latching means carried by said frame, means for sliding the frame to release the pins, and means for returning the latch frame to normal position.

35 7. In combination with a bowling alley, and a return, a wall having an outlet, the end of the return adjacent the outlet being spaced from the latter, a horizontal control in said space, and means to actuate the control so that the balls may gravitate therefrom and enter the outlet.

8. A toy bowling apparatus comprising a bowling alley, a frame at one end thereof and movable longitudinally thereof, a stationary frame, a plurality of pins pivoted thereto, a gravity latch for each pin carried

by the movable frame, means for moving the frame to release the pins, and means for returning the frame to normal position.

9. A toy bowling apparatus comprising a 50 bowling alley, a pin support near one end thereof, a plurality of pins pivoted thereto, a plurality of latches for supporting the pins out of the path of the balls on the alley, a movable frame, carrying the latches, 55 and means for moving said frame to release the pins.

10. A toy bowling apparatus comprising a bowling alley, a frame at one end thereof and movable longitudinally thereof, a 60 stationary frame, a plurality of pins pivoted thereto, a gravity latch for each pin carried by the movable frame, manually operated means for moving said frame to release the pins, an automatically operating means to 65 return the latches to pin supporting position.

11. In combination with a bowling alley and a support, pins swingably connected to the support, latching means to automatically hold the pins horizontally after striking thereof, means to effect relative movement between the support and latching means by sliding one away from the other so as to release the pins from the latter and 75 means to restore the elements to normal position after operation thereof.

12. In combination with a bowling alley and a support, pins swingably connected to the support, latching means to automatically hold the pins horizontally after striking thereof, and means to impart movement to all of the latches in unison by sliding same as a unit away from the pins to release the same from the pins.

In testimony whereof I affix my signature in presence of two witnesses.

JOHN F. McNAMARA.
